UNITED STATES PATENT OFFICE

CLAUDE S. STOUT, OF MARSHALL, MICHIGAN, ASSIGNOR TO MARSHALL FURNACE COMPANY, OF MARSHALL, MICHIGAN

HOT AIR HEATING SYSTEM

Application filed December 14, 1931. Serial No. 580,799.

The main objects of this invention are:

First, to provide an improved hot air heating system having means associated therewith for utilizing a gravity or a forced 5 air supply merely by controlling an electric fan or blower.

Second, to provide a forced air and gravity feed device for hot air heating systems in which there are no moving parts other 10 than the fan or blower.

Third, to provide an apparatus for use in heating systems which is very simple and compact in structure and easily installed either as a part of an original system or as 15 an attachment to heating systems of a type now very extensively used.

Objects relating to details and economies of my invention will appear from the description to follow. The invention is defined and pointed out in the claims.

A structure which is a preferred embodiment of my invention is illustrated in the accompanying drawings, in which:

Fig. 1 is a fragmentary perspective view 25 of a hot air heating system embodying my invention, no attempt being made to show the parts in relative proportions.

Fig. 2 is an enlarged fragmentary view 30 mainly in vertical section.

Fig. 3 is an enlarged fragmentary horizontal section illustrating the form and arrangement of the baffles or louvers which prevent back flow of the air when the blower is in operation.

Referring to the drawings, 1 indicates a hot air furnace provided with a hot air chamber 2 from which hot air is discharged by the flues or conduits 3. Cold air is supplied to the hot air chamber at the bottom 40 through the cold air boot or conduit 4.

At the outer end of this boot or conduit 4 is a cold air supply chamber 5 which in the embodiment illustrated is formed of metal lined with a sound deadening material. 45 Cold air, in the embodiment illustrated, is delivered to the top of this chamber by the cold air conduits 6. At one end the cold air chamber is provided with an opening closed by the removable closure or panel 7 which permits access to the blower 9 which, in the

embodiment illustrated, is driven by the electric motor 10.

The blower is supported by the stand or pedestal 11 secured to the floor of the cold air chamber. The electric conduit or cable 12 of the motor is connected to any suitable source of supply and is controlled through a switch, or thermostatically as desired, the switch or thermostat not being illustrated.

Between the cold air chamber and the hot 60 air chamber I arrange a rectangular frame 13 which carries the air directing cylinder or conduit 14 disposed in front of the fan and approximately at the center of the frame 13. This cylinder 14 is disposed with in and supported by a vertical panel 15 having a central opening 16 for the cylinder.

At each side of this panel 15 I arrange a plurality of rows of vertical spaced V or channel-shaped louvers or baffles 17, the louvers of adjacent rows being arranged in staggered relation as clearly illustrated in Fig. 3. These louvers face the hot air chamber. When the blower is not in operation air flows by gravity between these louvers and through the fan discharge or directing cylinder. However, when the blower is in operation the pressure within the boot and the hot air chamber tends to cause a back current or 70 back flow of air at the sides of the blower. This current of air striking the louvers sets up eddy currents therein which effectively prevents the back flow of air through the louver units of the intake.

The blower is thus enabled to operate efficiently to set up a forced draft of air through the hot air chamber. While the louvers effectively prevent the back flow of air, they do not objectionably obstruct the normal gravity flow when the blower is in 80 operative.

I thus provide an effective control apparatus without moving parts other than the blower. This results not only in economy and durability of structure and installation 95 but there are no loose parts to rattle or wear or become inoperative.

I have not attempted to illustrate or describe various modifications and adaptations which I contemplate as it is believed that this 100

disclosure will enable those skilled in the art to embody or adapt my improvements as may be desired.

Having thus described my invention, what I claim as new and desire to secure by Letters Patent, is:

1. In a hot air heating system, including a furnace having a hot air chamber, a cold air boot connected to said hot air chamber for supplying air thereto, a cold air chamber connected to said boot for supplying air thereto, cold air supply pipes connected to said cold air chamber, and a forced air supply unit disposed at the juncture between said cold air chamber and said boot, comprising a frame, a cylinder disposed in the center of said frame, a vertical wall having an opening for said cylinder, spaced baffles arranged in staggered relation from front to rear, facing the hot air chamber and carried by said frame in the space at the sides of said wall for allowing air to pass therethrough toward the hot air chamber but resisting the passage of air in the opposite direction, and a fan in said cold air chamber for forcing air through said cylinder as desired.

2. In a hot air heating system, including a furnace having a hot air chamber, a cold air boot connected to said hot air chamber for supplying air thereto, a cold air chamber connected to said boot for supplying air thereto, a forced air supply unit comprising a frame, a cylinder disposed in the center of said frame, a vertical wall having an opening for said cylinder, spaced V-shaped baffles arranged in staggered relation from front to rear, facing the hot air chamber and carried by said frame in the space at the sides of said wall for allowing air to pass therethrough toward the hot air chamber but resisting the passage of air in the opposite direction, and a fan for forcing air through said cylinder.

3. In a hot air heating system, including a furnace having a hot air chamber, a cold air boot connected to said hot air chamber for supplying air thereto, a cold air chamber connected to said boot for supplying air thereto, cold air supply pipes connected to said cold air chamber, and a forced air supply unit disposed at the juncture between said cold air chamber and said boot, comprising a cylinder disposed in the center of said boot, spaced vertical V-shaped baffles arranged in staggered relation from front to rear, facing the hot air chamber and carried by said frame in the space at the sides of said cylinder for allowing air to pass therethrough toward the hot air chamber but resisting the passage of air in the opposite direction, and a fan for forcing air through said cylinder toward said hot air chamber.

4. In a device of the character described, the combination with a heating chamber, of a blower for forcing air into said chamber,

and stationary means in parallel with said blower for normally allowing the passage of air into said chamber by gravity but resisting the escape of air therefrom, said means comprising baffles having channels facing said chamber.

5. In combination, a furnace, an air conduit associated with said furnace, a cylindrical wall disposed within said conduit, a blower for forcing air through said cylindrical wall, and stationary louvers disposed in the conduit in the space between said wall and sides of the conduit for normally allowing the passage of air in one direction, but resisting the passage of air in the other direction.

6. In combination, a furnace, an air conduit associated with said furnace, a cylindrical wall disposed within said conduit, and stationary louvers disposed in the conduit in the space between said wall and sides of the conduit for normally allowing the passage of air in one direction, but resisting the passage of air in the other direction.

7. In a device of the character described, the combination with a heating chamber, of means for forcing air into said chamber, and stationary baffles in parallel with said means for normally allowing the passage of air into said chamber by gravity but resisting the escape of air therefrom.

8. In combination, a furnace, an air conduit including a forced air passage associated with said furnace, means for forcing air through said passage, and stationary louvers disposed in the conduit in the space between said passage and sides of the conduit for normally allowing the passage of air in one direction, but resisting the passage of air in the other direction.

9. In a device of the character described, the combination with a heating chamber, a conduit for directing air to said chamber, and stationary means in said conduit normally allowing the passage of air into said chamber, but resisting the escape of air therefrom, said means comprising baffles having channels facing said chamber.

10. In combination, a furnace, an air conduit associated with said furnace, a small pipe disposed within said conduit, a fan for forcing air through said pipe, and stationary louvers disposed in the conduit in the space between said pipe and sides of the conduit for normally allowing the passage of air in one direction, but resisting the passage of air in the other direction.

11. The combination with a heating chamber, of a cold air inlet chamber, a blower disposed centrally thereof, and sets of V-shaped louvers disposed at each side of said blower arranged in staggered relation and facing said heating chamber permitting passage of air by gravity to said heating chamber but acting to obstruct the passage of air from

said heating chamber when said blower is in operation.

12. The combination with a heating chamber, of a blower delivering to said chamber, a gravity flow air connection for said chamber, and a plurality of rows of V-shaped louvers disposed in said gravity flow air connection in spaced staggered relation, facing said heating chamber and permitting the flow of air by gravity to said heating chamber by acting to obstruct the passage of air from said heating chamber when pressure is created therein by the operation of said blower.
- 15 13. The combination with a heating chamber, of a cold air inlet chamber therefor, a blower delivering to said heating chamber, there being a gravity passage from said cold air inlet chamber to said heating chamber, and a plurality of channeled fixed louvers disposed in said gravity flow air passage in multiple series in staggered relation and facing said heating chamber.

In witness whereof I have hereunto set
25 my hand.
